UNITED STATES PATENT OFFICE.

CARL S. HOMSHER AND WILLIAM E. LAWRENCE, OF DENVER, COLORADO.

FOLDABLE IRONING-BOARD.

995,142.

Specification of Letters Patent. Patented June 13, 1911.

Application filed January 10, 1911. Serial No. 601,800.

To all whom it may concern:

Be it known that we, CARL S. HOMSHER and WILLIAM E. LAWRENCE, citizens of the United States, residing at Denver, in the county of Denver and State of Colorado, have invented new and useful Improvements in Foldable Ironing-Boards, of which the following is a specification.

The invention relates to ironing boards, and more particularly to the class of foldable ironing boards.

The primary object of the invention is the provision of an ironing board in which a single support is employed, and that may be attached to a table, window casing or other convenient place for use.

Another object of the invention is the provision of an ironing board in which the single support thereof will be sustained in folded position when the ironing board is detached or removed from the table, shelf, or window casing, when not in use.

A further object of the invention is the provision of an ironing board in which the single support thereof is extensible, whereby the board may be sustained at the proper elevation for the convenient use thereof by a person, after it has been clamped to a table top, shelf or window casing.

A still further object of the invention is the provision of an ironing board of this character which is simple in construction, strong, durable, thoroughly reliable and efficient in operation, and inexpensive in manufacture.

With these and other objects in view, the invention consists in the construction, combination and arrangement of parts, as will be hereinafter more fully described, illustrated in the accompanying drawings, and pointed out in the claim hereunto appended.

In the drawings: Figure 1 is a side elevation of an ironing board constructed in accordance with the invention, and shown in position for use. Fig. 2 is an end elevation thereof. Fig. 3 is a transverse sectional view on the line 3—3 of Fig. 1. Fig. 4 is a bottom plan view of the ironing board when in folded position. Fig. 5 is a vertical longitudinal sectional view thereof. Fig. 6 is a sectional view on the line 6—6 of Fig. 1. Fig. 7 is a fragmentary enlarged transverse sectional view through the ironing board, showing in detail the adjustable bearing plate.

Similar reference characters indicate cor-

responding parts throughout the several views of the drawings.

Referring to the drawings by numerals, 5 designates the ironing board proper which is tapered toward one end, and is preferably made from wood, although the same may be made from any other suitable material, the smaller end of the board being pointed, as at 6, to permit the ironing of seams of waists, skirts, or similar garments, without wrinkling.

Secured in any suitable manner to the under face of the board 5, spaced from its rear end, is a triangular-shaped spacer piece 7, the same being of the required thickness, and it may be of any other desirable shape, if found expedient. To the inner end of the spacer piece 7 is secured a hinge 8, the same being also secured to a clamping lever or strip 9 for the purpose of clamping the ironing board 5 to a table top, shelf, window casing, or other stationary part, so that the said ironing board may be used in the ordinary manner.

Suitably secured to the forward end of the spacer piece 7 is a pair of hinges 10, the same being also secured to a supporting leg or prop 11, the hinges 10 being adapted to permit the swinging of the leg or prop 11 toward and away from the board 5. This prop or leg 11, when swung at right angles to the board 5, serves to hold the latter in substantially horizontal position for use, the said leg or prop 11 being provided with a rectangular shaped central opening 12, through which projects the clamping lever or strip 9, when said leg or prop 11 is at right angles to the board 5, the said clamping lever or strip 9 being frictionally in contact with the inner wall of the said opening 12, thus holding the said clamping lever at a forward inclination when the table top, shelf, window casing, or other stationary part is engaged between the contiguous ends of the latter and the board 5, respectively, thereby holding the latter clamped to such stationary part.

Secured to the prop or leg 11 spaced from its hinges 10 is a suitable bearing 13 in which is engaged a swinging loop 14 which is adapted to lock with a keeper 15 fixed to the clamping lever or strip 9, when the leg or prop 11 has been swung at right angles to the board 5, thus preventing the said leg or prop from accidentally folding inwardly toward the said board. However, it is ob-

vious that when the loop 14 is disengaged from the keeper 15, the leg or prop 11 may be readily swung inwardly against and parallel with the board 5, whereby it may be stored in the least possible space when not in use.

Spaced a distance forwardly of the spacer piece 7 and suitably secured in the under face of the board 5 is an eye member 16, to 10 which is connected one end of a coiled retractile spring 17, the same being trained through a central notch 18 formed in the forward end edge of the clamping lever or strip 9 and has its opposite end formed with 15 a ring 19 detachably engaged with a hook member 20 fixed to the outer face of the said clamping lever or strip 9 spaced from its notched end edge 18, the spring 17 being designed to act upon the clamping lever or strip 9 so that it will hold the leg or prop 11 in folded position parallel with and against the board 5. Secured near the notched end edge 18 of the clamping lever or strip 9 is a guide eye 21, through which 20 is trained the spring 17, whereby the latter will be prevented from lateral displacement during the folding and unfolding of the leg or prop 11 toward and away from the board proper.

30 The leg or prop 11 is formed with diverging slots 22 opening through the free end edge thereof, and in these slots are disposed independently adjustable extension bars 23, the same being held in the slots by 35 means of guide cleats 24 disposed transversely of the said slots 22 at opposite sides of the prop or leg 11, the said guide cleats 24 being suitably fixed to the said opposite faces of the leg or prop. Mounted for sliding movement in the leg or prop 11 are locking bolts 25, the same being adapted for engagement in suitable sockets 26 formed in the extension bars 23 when the said sockets 26 align with the locking bolts 25, the sockets 40 45 50 55 60 65 70 75 80 85 90 95 100 105 110 115 120 125 130 135 140 145 150 155 160 165 170 175 180 185 190 195 200 205 210 215 220 225 230 235 240 245 250
